Primary Examiner — Richard Edgar*Assistant Examiner* — David Truong(74) *Attorney, Agent, or Firm* — Omni Legal Group;
Omid E. Khalifeh; Ariana Santoro(57) **CLAIM**

The ornamental design for a jar, as shown and described.

DESCRIPTION

FIG. 1 is a front perspective view of a jar according to the present invention;

FIG. 2 is a first side view of a jar according to the present invention;

FIG. 3 is a second side view of a jar according to the present invention;

FIG. 4 is a third side view of a jar according to the present invention;

FIG. 5 is a fourth side view of a jar according to the present invention;

FIG. 6 is a top view of a jar according to the present invention; and,

FIG. 7 is a bottom view of a jar according to the present invention.

The broken lines shown in the drawings are for the purpose of illustrating portions of the jar and form no part of the claimed design.

1 Claim, 7 Drawing Sheets(56)
